UNITED STATES PATENT OFFICE.

CHARLES F. WISLOH, OF NEW YORK, N. Y.

WATER-COOLER.

SPECIFICATION forming part of Letters Patent No. 296,095, dated April 1, 1884.

Application filed January 25, 1884. (No model.)

To all whom it may concern:

Be it known that I, CHARLES F. WISLOH, of the city, county, and State of New York, have invented certain new and useful Improvements in Water-Coolers, of which the following is a specification.

This invention has reference to improvements in water-coolers in which the water is cooled without being in contact with the ice and delivered in a clean and filtered state; and the invention consists of a water-cooler the body of which is made of two parts—a fixed lower part and detachable upper part. A glass reservoir with funnel-shaped lower end is supported at the interior of the body, the funnel being jointed to the inner end of the discharge-faucet. The ice is supported in a net around the funnel, which is protected by a wire guard-cone against injury by the ice.

20 In the accompanying drawings, Figure 1 represents a vertical central section of my improved water-cooler; and Fig. 2, a vertical transverse section of the same on line *xx*, Fig. 1.

25 Similar letters of reference indicate corresponding parts.

A represents the body of a water-cooler, which is made of cylindrical or other shape. The body A is made of two parts, the lower part of which is secured to the base B, while the upper part is made detachable and tightly fitted to the lower part by an overlapping joint. To the base is applied a sheet-metal cylinder, B', that is extended above the joint between the upper and lower parts of the body, so as to receive the dripping from the ice. A frame consisting of stout upright rods D and a horizontal top ring, D', is secured to the base, and serves to support the water-receptacle E, which is made of cylindrical shape, and provided with a funnel-shaped lower end. The lower end of the funnel E' is supported by and tightly packed to the inner end of the barrel of the discharge-faucet F, as shown in Fig. 1. 45 By removing the water-receptacle E from the cooler it can be readily cleaned whenever desired. The water-receptacle E is provided at the base, at the point where it is contracted for the funnel E', with a filter, F', that is made

of perforated plates, and an intermediate layer 50 of charcoal or other suitable filtering material. The ice is broken into lumps and placed into a net, G, that is suspended from a ring-shaped wire, g, supported on radial arms g'. The net G is preferably provided at its inside 55 with a layer of flannel to retain the impurities contained in the ice, which net is removed from time to time and cleaned by washing. A wire guard-cone, E², is placed around the funnel E', and at the upper end supported by the radial rods g', and at the lower end by radial rods g'', attached to eyes of the supporting-rods D. The guard-cone E² protects the funnel E' and prevents the breaking of the same by the lumps of ice.

65 The ice-water is collected in the cylinder B' at the lower part of the cooler and drawn off from time to time through a discharge-tube, f, the outlet-orifice of which is closed by a screw-plug, f'. The ice is placed into the supporting-net, after lifting the upper part of the body A off the lower part. As the ice-water is collected in the lower part of the cooler, and not in contact with the ice, the latter will last much longer. As the ice is not placed 70 into the water, the latter is drawn off in a cold and perfectly pure and filtered state without any impurities contained in the ice, so that the cooler is better adapted for domestic purposes.

75 Having thus described my invention, I claim as new and desire to secure by Letters Patent—

1. The combination of an exterior body, an interior water-receptacle having a funnel-shaped end, an interior supporting-frame for the water-receptacle, an ice-receptacle arranged around the funnel of the water-receptacle, and a discharge-faucet connected to the lower end of the funnel, substantially as set forth.

85 2. The combination of an exterior body, A, an interior water-receptacle, E, having a funnel, E', an interior supporting-frame, D, D', for the water-receptacle, an ice receptacle or net, G, arranged around the funnel E', a guard-cone, E², arranged around the funnel, and a discharge-faucet, F, connected to the lower 90 end of the funnel, substantially as specified.

3. The combination of the body A, made of an upper detachable and a lower fixed section, a base, B, having a cylinder, B', an interior water-receptacle, E, having a bottom filter, F', and funnel E', a supporting-frame, D' an ice-supporting net, G, a guard-cone, E², around the funnel E', and a discharge-faucet, F, connected to the lower end of the funnel E', substantially as specified.

In testimony that I claim the foregoing as my invention I have signed my name in presence of two subscribing witnesses.

CHARLES F. WISLOH.
